US00D747666S

(12) **United States Design Patent**
Yatsugi-Kang

(10) **Patent No.:** **US D747,666 S**
(45) **Date of Patent:** **** Jan. 19, 2016**

(54) **EARRING**

(71) Applicant: **HARRY WINSTON SA,**
Plan-les-Ouates (CH)

(72) Inventor: **Rie Yatsugi-Kang**, Cresskill, NJ (US)

(73) Assignee: **HARRY WINSTON SA,**
Plan-les-Ouates (CH)

(**) Term: **14 Years**

(21) Appl. No.: **29/510,015**

(22) Filed: **Nov. 24, 2014**

(30) **Foreign Application Priority Data**

May 22, 2014 (WO) DM/083 634

(51) **LOC (10) Cl.** **11-01**
